UNITED STATES PATENT OFFICE.

WALTER RICHMOND, OF GLENELLYN, ILLINOIS.

SANITARY NURSING BOTTLE.

Application filed July 6, 1922. Serial No. 573,139.

To all whom it may concern:

Be it known that I, WALTER RICHMOND, a citizen of the United States, residing at Glenellyn, in the county of Du Page, State 5 of Illinois, have invented certain new and useful Improvements in Sanitary Nursing Bottles; and I do hereby declare the following to be a full, clear, and exact description of the invention, such as will enable others 10 skilled in the art to which it appertains to make and use the same.

This invention relates to a nursing bottle which is more sanitary than those in common use, and has special reference to one in 15 which the nipple can be placed in position with the greatest ease and with no danger of upsetting the bottle in the operation.

By referring to the drawings it will be seen that, to place the nipple in position, it 20 is not necessary to handle the inside portion of the nipple or the mouth of the bottle as must be done when placing the nipple on nursing bottles in common use. My invention, therefore, covers a strictly sanitary 25 nursing bottle.

To attach the nipple, according to my invention, it is merely necessary to set the nipple on the curved top of the bottle (the curved top acts as a guide and spreader) 30 and press downward with a firm steady pressure, either with the hand or with the special nipple-seating tool shown in the drawings, until the nipple reaches its proper position. The operation is simple and positive and eliminates any possibility of upsetting the bottle or spilling the contents 35 even by persons unskilled in the placing of the nipple.

The preferred form of the invention is 40 shown in Fig. 3, where the guide and spreader is integral with the receptacle; although I have made guides and spreaders and attached them to the receptacles, it is also possible to get results by using a guide 45 and spreader as shown in Fig. 5, which is a ring adapted to fit in the mouth of the receptacle Fig. 6. After its action of guiding and spreading the nipple into place on the receptacle Fig. 6, the ring remains inside the 50 nipple while the nipple is firmly held by the bead (9), until such time as the nipple is removed, when all parts can be separated and thoroughly sterilized.

The guide and spreader portion 5 engages 55 and braces the walls of the nipple Fig. 4

when in place on the bottle Fig. 3 and prevents collapsing of the nipple.

Referring now to the drawings, Fig. 1 is a side view of a nursing bottle showing a bead (1) near the top for holding the nipple in place, also the curved top of the bottle 60 (2) which acts as a guide and spreader to carry the nipple into place when a downward pressure is exerted.

Fig. 2, directly above the bottle, ready to 65 be put in place, is the nipple showing the thickened or reinforced rim (3) and a portion of the nipple turned up on the outside. This turned up portion will snap over the bead or ridge (1) on the bottle, after the 70 nipple has been spread to its proper diameter by the spreader (2) in consequence of a steady downward movement either of the hand or of the special nipple-seating tool shown in Fig. 7. The action is to first spread 75 the opening in the nipple and then guide it into place where it will snap over the bead (1) and have a firm hold on the nursing bottle without the necessity of touching the inside of the nipple or the mouth of the bottle. 80

In operation, the nipple is set down on the guide and spreader portion (2) of the bottle Fig. 1, and the fingers grip the nipple just above the turned up rim portion (3) 85 and with a steady downward pressure the nipple is spread to its proper diameter and finally the turned up portion (3) is snapped over the ridge portion (1) of the bottle.

Fig. 3, is a side view of a nursing bottle 90 showing a groove (4) near the top and just above this the guide and spreader portion (5). The nipple, Fig. 4, which is used with this bottle terminates in a ring (6) extending both inwardly and outwardly from the wall of the nipple, which adapts it to fit 95 snugly into the groove (4).

In operation by placing the nipple, Fig. 4, on the guide and spreader portion (5) and exerting a steady downward pressure, the nipple is first spread and then snaps 100 into place without the necessity of handling either the inside of the nipple or the mouth of the bottle and the extended upper portion 5 supports the walls of the nipple against 105 collapsing.

Fig. 5, is a ring of suitable material having a cone shaped upper portion (7) to act as a guide and spreader, while the lower portion (8) is a flange adapted to fit into the mouth of a receptacle such as Fig. 6, 110

thus making a removable sanitary guide and spreader for nursing receptacles.

Fig. 6 shows a nursing receptacle with the lower portion cut away and a bead (9) at its upper end for holding a nipple in place.

Fig. 7, is a side view of a nipple (10) showing a portion of the nipple-seating tool (11) in position for forcing a nipple into place on a receptacle.

10 12, 13, 14 and 15 are fingers with blunt ends for engagement with the nipple while the other ends are secured in a handle (11). In order to make the drawing clearer, two fingers opposite 13 and 14 are not shown.

15 By the use of this nipple-seating tool the nipple can be forced into position without any portion of the nipple being touched by the human hands after sterilization.

Having thus described the invention,
20 what is claimed as new is:

1. A sanitary nursing bottle comprising a receptacle and being provided with nipple retaining means adjacent the mouth thereof, that portion of the bottle beyond the said

means being extended a substantial distance 25 whereby when the nipple is in position on the bottle the said extended portion engages and braces the walls thereof against collapsing.

2. A sanitary nursing bottle comprising a 30 receptacle and being provided with nipple retaining means adjacent the mouth thereof, that portion of the bottle beyond the said means being detachable and being extended a substantial distance whereby when 35 the nipple is in position on the bottle the said extended portion engages and braces the walls thereof against collapsing.

3. A nipple seating tool comprising a 40 head, arms extending therefrom said arms at the free ends thereof being provided with blunted nipple engaging portions.

In testimony whereof I affix my signature in the presence of two witnesses.

WALTER RICHMOND.
